JUSTIFICATION RULE

William G. Turquand, Brooklyn, N. Y., assignor
to Underwood Elliott Fisher Company, New
York, N. Y., a corporation of Delaware

Application June 13, 1939, Serial No. 278,894

4 Claims. (Cl. 33—107)

This invention relates to devices for use in justifying typed matter, and more particularly to measuring devices or rules by which the degree of justification required may be determined.

5 In justifying typed matter a typewriter equipped with a justifying mechanism is used, whereby the operator may preselect a certain one of a plurality of carriage feed means for each line, respectively, that is to be typed, so that the 10 typewriter carriage, in its letter-feed movement during subsequent operation, will automatically expand or contract the line to terminate exactly at a certain predetermined line length, and the finished typed matter presents an arrangement

15 wherein all the lines, being justified, form an even right-hand margin. Where justifying of typed matter to an appreciably different line length from that in which the original typing is done, is required, it has been heretofore necessary to retype the matter without justifying, at the new line length, preparatory to typing the justified copy. In such cases by the use of a suitable measuring device, the retyped, unjustified copy in the new line length is marked off 20 to show the typist the degree of expansion or contraction required in each typed line, so that after retyping on a justifying typewriter, the lines all terminate at a prescribed even margin. Occasionally, the justified copy is to be typed on 25 a machine having a different kind of type, and therefore different letter-spacing, than that of the original typed matter, and yet the justified typing is to be of a prescribed line length so as, for instance, to occupy a certain width in a previously printed form. This circumstance in the past has also necessitated a preliminary unjustified retyping on a machine having the kind of type required for the justified copy, before the justified copy could be made.

30 One of the objects of this invention is to provide a rule that is universally adaptable in the justification of typed matter, being adapted for use in determining the degree of justifying required for the arrangement of any typed matter, 35 regardless of the variations in line lengths, the different kinds of type of the original or justified typing, or the relative positions of the individual typed lines in the original typed matter.

35 Another of the objects of the invention is to provide a measuring device or rule by which justification of typed matter in an appreciably different line length than that of the original copy may be readily determined without retyping a preliminary unjustified copy at the new line length, as is usually necessary.

A further object is to provide a device of this character by which the degree of justifying may be determined, notwithstanding that the justified copy is to be typed on a machine equipped with different type than that on which the original unjustified matter has been typed; thus the device may be used to determine justifying of matter originally typed in "pica" type, in an instance where the justified copy is to be typed on a machine equipped with "elite" type, or vice versa, 10 without the necessity of making a retyped unjustified copy.

15 Other objects and advantages will hereinafter appear.

In the drawings:

Fig. 1 is a perspective view of the justifying rule, illustrating one side of the rule for justifying in "pica" type.

Fig. 2 is a fragmentary perspective view of the justifying rule shown in Fig. 1, illustrating 20 the reverse side of the rule for justifying in "elite" type.

Figs. 3 and 4 illustrate an example of the work that may be accomplished by use of the invention; Fig. 3 representing a typical unjustified 25 typed sheet that has been marked off by use of the rule, preparatory to justifying to a new line length; Fig. 4 illustrating the typed matter shown in Fig. 3, retyped on a justifying typewriter to the new line length, and justified so 30 that each line terminates exactly at a predetermined right-hand margin.

Figs. 5 to 10 inclusive illustrate the procedure followed by the typist in using the invention to determine the new line length and the degree 35 of justification required by each typed line, and demonstrates the method by which the justifying markings shown in Fig. 3 are determined. Figs. 5, 6, and 7 illustrate the method as applied to the first typed line of the original typing, and 40 Figs. 8, 9, and 10 illustrate the method as applied to the second or a succeeding line of original typing.

Referring now to the accompanying drawings for a more detailed description of the invention, 45 and more particularly to Figs. 1 and 2, the justifying rule includes an elongate body portion 11, preferably equipped at its ends with suitable abutments 12 and 13 to prevent dislodgement and facilitate the setting of certain slides hereinafter 50 described. In accordance with the invention, the rule has a line-length scale 14 arranged longitudinally preferably along an edge of body portion 11, graduated in the letter spacing for a typewriter equipped, for example, with "pica" 55

type; the spacing of each graduation being therefore at $\frac{1}{10}$ inch, or ten letter spaces per inch. Preferably on the opposite face of the rule 11, along an edge opposite that on which the scale 14 is arranged, a line-length scale 15 is provided, as illustrated in Fig. 2, the same being graduated in accordance with the letter spacing of a typewriter equipped with "elite" type, the spacing of each graduation being therefore $\frac{1}{12}$ inch apart, there being twelve letter spaces per inch of an "elite" typed line. Each scale 14 and 15 has a zero point or pointer at its beginning and, for reasons hereinafter manifest, the zero points of each scale coincide and each zero is a like distance from the abutment 12. The scales 14 and 15 are arranged on opposite faces of the rule to avoid confusion in use, and are arranged at opposite longitudinal edges of the rule so that each scale may have a corresponding position along a typed line, and reference to either scale may be had by merely rotating the rule on its longitudinal axis.

Toward the left-hand end of the rule is slidably carried a zero-indicating slide 16, the right-hand edge 17 at each face of which represents a zero or gaging marker for cooperation with each scale 14 and 15 of the rule, the slide 16 having a corresponding panel on each side thereof. For convenience in setting the slide 16 to the zero position on either scale 14 or 15, the abutment 12 is provided, the zero point of each scale 14, 15, being at a distance from the abutment 12 equal to the width of the slide 16.

The rule is further equipped at its right-hand portion with a justifying slide 18 adapted to be positioned along the body portion 11 at any setting desired. The justifying slide 18 is adapted to cooperate with either scale 14 or 15, and is equipped on one face thereof, as shown in Fig. 1, with a justifying scale 19 presenting a short series of letter-space calibrations corresponding in spacing to the scale 14. On its opposite face the slide 18 has a justifying scale 20 similar to the scale 19 but spaced in accordance with that of scale 15. For convenience in setting the justifying slide 18 to a certain reading on the line-length scales 14, 15, the calibration lines marking the justifying scales 19 and 20 are extended to project over the line-length scales, and the opposite face panels of slide 18 are preferably of transparent material so that scales 14 and 15 may be viewed therethru. Each side of the rule may be suitably identified to indicate the letter spacings to which the scales 14 and 19 and the scales 15 and 20 are calibrated, preferably by marking the slide 18 on each face with the name of the type represented thereby, as shown.

It will be noted that each of the scales 19 and 20 are divided off into six letter spaces which collectively represent an arbitrary line-length distance within which any typed line may be justified, each of the spacings of the scales 19 and 20 being consecutively numbered or otherwise identified to indicate to the typist the degree of justification required. As will be hereinafter further explained, one of the calibrations, preferably the numeral "4", on each of the scales 19 and 20 represents a "neutral" or normal justifying range. In order that the two justifying scales be coordinated with each other for the purposes of converting the type from one kind of type to another, it is desired that the respective numerals of the scales 19 and 20 representing the normal range, be in columnal alignment with each other, although these numerals be on opposite faces of

the justifying slide. By this correlation, the slide 18 may be set to a line length of a certain number of letter spaces on either scale 14 or 15, and the corresponding justifying scale 19 or 20 will be spaced from the zero point of its line-length scale the same lineal distance; a feature advantageous in converting typing from one kind of type to another. 5

As afore indicated, the justifying rule of the invention is intended for use in conjunction with various kinds of justification typewriters equipped with justifying mechanisms having a calibrated selector member by which the operator may pre-select a certain justifying means, which in effect varies the letter-feed movement of the carriage to modify the line length in accordance with the setting of the justifying selector member. Justifying mechanisms of this character, as for example that shown in the patent to Dodd, No. 2,118,343, have the selector device usually numbered from one to six, by which calibrations the operator preselects the setting for the desired degree of justification. For example, if it is found that a certain typed line on the unjustified copy is to be expanded a distance equivalent to three letter spaces, the operator sets the justifying device accordingly, and the machine, during subsequent typing, will automatically expand the new typed line a distance of three letter spaces. This process is carried through for each succeeding line, the justifying device being reset to the degree of justification required for each individual line, so that the finished justified copy has all of the typed lines terminating at an even right-hand margin. It is to be noted that the numerals on each of the justifying scales 19 and 20 relate to the calibrations on the selector device of the typewriter, and should, therefore, preferably correspond therewith so as to directly indicate to the operator the setting of the justifying mechanism to be used. 30

The procedure followed in determining the new line length and the degree of justification required for each typed line of the justified copy, will now be described in relation to an instance 45 wherein the justified copy is to be typed at a line-length shorter than that of the original or unjustified typed matter. It may be assumed, for example, that the original typed matter is that illustrated in Fig. 3, in which a line length 50 of approximately five inches is shown, and the typed matter in the justified copy is to be of a line length exactly four inches long. The procedure demonstrated in Figs. 5 to 10 inclusive presumes that the original typing is done in 55 "pica" type and that the justified copy is to be typed on a machine also of "pica" type. The procedure is as follows:

The zero indicator slide 16 is set at the zero of the line-length scale 14 by sliding same leftward along the rule against the abutment 12 at which position edge 17 will be at the zero of scale 14. The justifying slide 18 is set along the scale 14 so that the numeral "4" of scale 19 is in registry with the numeral "40", on scale 14, the numeral "40" being chosen in that the justified copy is to be in a four-inch line length, or 40 letter spaces of "pica" type in length. The numeral "4" of the scale 19 is chosen in order that the justifying may be effective to either shorten 70 or lengthen the justified line to the predetermined line length of forty letter spaces, it being understood that the machine on which the justified copy is to be typed has its justifying device calibrated in this manner; that is, that the range 75

of justifying represented by the numeral "4" on the selector device of the machine is the "neutral" or normal range and is such that the carriage will be advanced at the normal letter-feed rate of forty letter spaces in a four inch line of "pica" type. From this it will be seen that the numerals "1" "2" and "3" on scale 19, being less than the numeral "4" represent ranges of justifying by which a lesser number of letters than forty may be so spaced as to fully occupy a normally forty letter-space line; and the numerals "5" and "6" on scale 19, being greater than the numeral "4," represent ranges of justifying by which a greater number of letters than forty may be typed in a line of forty normal letter spaces. The justifying scale 19 could be calibrated consecutively from the "neutral" calibration to the right and left thereof and thus be consistent with the actual justification effect obtained in the typewriter of the Dodd patent, but such a scale might be confusing to the operator as there would be both positive and negative calibrations of the same numerical value. It will be observed that the "neutral" or normal range of justifying may be represented by any one of the numerals on the scales 19 and 20, providing, of course, that the justifying typewriter be correspondingly calibrated; in which case that numeral of scale 19 representing the normal range, is set in registry with the numeral on scale 14 representing the desired line-length for the justified copy.

The justifying rule, so conditioned, is laid along the first-typed line of the unjustified copy, as shown in Fig. 5, with the zero indicator edge 17 of the slide 16 just to the left of the first letter in the typed line. By observing the position, relatively to the scale 19, of the last letter of the word ending within the length of this scale, the range of justifying for the first retyped line may be noted. As shown in Fig. 5, the last letter of that word is in line with the numeral "4" of scale 19. For convenience to the typist, this last letter may be identified as by canceling same, and the reading of scale 19 is recorded over that letter, that is a numeral "4" is marked directly over the identified letter, as shown in Fig. 6. In that the typing of the justified copy is to be at a shorter line length than the unjustified copy, there remains an additional length in the first line of the unjustified copy, which length is to be incorporated in the second line of the justified copy.

The remaining line length of the first line is now recorded on the rule in the following manner, with reference to Fig. 7. The rule is moved bodily along the first line until the zero indicator edge 17 of slide 16, still at the zero of scale 19, is just to the left of the first letter of the first word in the remaining line length, as shown in phantom in Fig. 7, and, while maintaining this position of the body portion 11 of the rule, slide 16 is moved rightward along the rule until the zero edge 17 thereof is just to the right of the concluding letter of the line, that is, to the position shown in full line in Fig. 7.

It will be noted that in this manner, the remaining line length of the first line of the unjustified copy has been recorded on the rule preparatory to completing the measurement of the second justified line. This is done as shown in Fig. 8, by aligning the rule in its present condition with the second line of typing, locating the zero edge 17 just to the left of the first letter thereof. It may be here noted that during

this procedure, the justifying slide 18 is maintained in the same position at all times, that is, numeral "4" of the scale 19 thereof is always aligned with the numeral on scale 14 representing the line length, in the present instance the numeral "40." The last letter of the word ending within the justifying scale 19 is noted and conspicuously marked as aforescribed, and the reading of scale 19 over this letter is recorded, as shown in Fig. 9. It will be seen, however, that this letter is marked with a "3" although the last letter is at the "2" calibration of scale 19. In other words, "one" has been added to the reading of scale 19 to inject an additional letter (word) space in the justified line, which space will occur between the last word of the first line and the first word of the second line, of the unjustified copy. Fig. 10 shows the manner of recording on the rule the remainder of the second line, the procedure being similar to that described for the remainder of the first line, shown in Fig. 7. All the typed lines of the unjustified copy are similarly measured and marked.

If the line length in the justified copy is to be longer than the average line length in the original typing, the procedure is somewhat similar to that previously described, except that instead of recording on the rule a remaining line length as shown in Fig. 7, an entire line length is recorded on the rule. In this instance the procedure is as follows:

With slide 16 at zero and slide 18 set at the desired line length, the rule is laid along the first line with the zero edge 17 in the position shown in Fig. 5. In this instance, however, the slide 18 will be beyond the end of the line. Holding the rule in this position, the slide 16 is moved along the rule until its edge 17 is just beyond the terminal letter of the line, that is, to the position of slide 17 shown in full in Fig. 7. The first line of the unjustified copy has thus been recorded on the rule and the additional line length required to complete the justified line is measured off the initial portion of the second unjustified line, by positioning the rule in its present condition at the second line substantially as shown in Fig. 8. The terminal letter of the word ending within the scale 19 will be the last letter in the justified line, and this letter is marked and numbered to indicate the degree of justification required, substantially as illustrated in Fig. 9. A similar procedure is followed for all the succeeding lines of the unjustified copy, by first recording on the rule, by manipulating the zero indicator slide 16, any one line or remainder of the line which in itself is insufficient to complete the length of the justified line.

It is necessary that the operator observe a few simple rules in combining, in a justified line, the remaining portion of one line with a complementary portion of a succeeding line in the unjustified copy. These rules are briefly as follows: If the typewritten line of the unjustified copy ends with a word, one letter space is to be added to the reading of scale 19 in the marking of the terminal letter of that line for justifying. If the line of the unjustified copy ends with a hyphen, one space should be dropped; that is, the reading of scale 19, less one, will be recorded. If the typewritten line ends with a period, two letter spaces should be added to the reading of scale 19. The last rule applies as well where the unjustified line ends with a comma, colon, semi-colon, or quotation marks. It is to be understood, however, that in taking the reading of the scale 19 the actual

letter preceding the punctuation mark is to be regarded as the last letter of that line, and not the punctuation mark itself. This practice is advised as it will eliminate any uncertainty as to the limit of the letter-space occupied by the punctuation mark.

In the foregoing is described the procedure followed in marking unjustified typed matter for justification, at the same time changing the line length. Where the same line length is to be used for the justified copy as was used for the unjustified copy, the justifying rule may be used as follows: The zero indicator slide 16 is set at zero against the abutment 12; and, with the zero edge 17 aligned just to the left of the first letter of a typed line, the justifying slide 18 is moved along the rule to that position wherein all of the typed lines at their right-hand ends terminate somewhere within the justifying scale 19, that is, at the position where all of the typed lines end within a vertical margin bounded by the first and last calibrations of scale 19. With the rule in this condition, the justification for each typed line is individually determined, recording the reading of scale 19 adjacent each line end, as previously described.

The use of the justifying rule for converting from one kind of type to another, that is, for example, where the unjustified copy is typed in "pica" type and the justified copy is to be in "elite" type, will now be described. Where an exact length of line in the justified copy is not required and the slight change in line length by converting from one kind of type to another is immaterial, and it is only required to justify the typed matter, the procedure is the same as that just described for an unchanged line length, using the scale on the rule corresponding to the kind of type in which the unjustified matter is typed. Where, however, an exact length of line in the justified copy is required and a machine of a different kind of type is to be used, which in itself changes the line length, the procedure is as follows:

The zero indicator slide 16 is set at the zero of the line-length scale, and the justifying slide 18 is set so that the numeral "4" is in registry with the numeral representing the desired line length of the justified copy, however, using the line-length scale 14 or 15 corresponding to the kind of type in which the unjustified copy has been typed. For example, if it is determined that the justified copy is to be done in "elite" type, the lines to be of fifty letter-spaces in length, and the unjustified matter is in "pica" type, the slide 18 is set with its numeral "4" in registry with the "50" on the "pica" scale 14. Thus, the rule is in condition for marking off the unjustified copy for justifying. The scale 14 which corresponds to the kind of type ("pica") in the unjustified copy, is now laid along each line of the unjustified typed matter, proceeding substantially as previously described for a changed line length but an unchanged kind of type. Each line of the unjustified typing, or part thereof is marked off to indicate the terminal letters for the justified line and the degree of justification required. In that the required line length for the justified copy has been introduced in the rule in setting same, when the justified copy is typed on a justifying machine each line will terminate at an even right-hand margin and the lines will all be of the prescribed length.

It will be seen from the foregoing that the justifying rule constructed in accordance with

the invention, embodies a measuring device that is universally adaptable in the justification of typed matter, notwithstanding that there may be variations between the line lengths of the unjustified and justified copy, that there may be different kinds of type used in the respective typed matter, and notwithstanding that the relative positions of the individual typed lines in the unjustified copy may vary appreciably. By following a few simple rules of procedure, the typist may readily determine the extent of justification required for substantially any typed matter.

Although in this application, there is specifically described, one embodiment which the invention may assume in practice, it will be understood that same is shown for the purposes of illustration, and that the invention may be modified and embodied in various other forms without departing from its spirit or the scope of the appended claims.

What is claimed is:

1. A justifying rule, comprising in combination, an elongate body, a first line-length scale graduated in letter spacings for a certain kind of type, a second line-length scale graduated in letter spacings for a different kind of type, said line-length scales being coextensive on said body and having coincident zero points, a zero indicator slide on said body having pointers adapted to cooperate with each of said line-length scales, and a justifying slide on said body slidably to selective line-length positions along said line-length scales, said justifying slide including a first justification-indicating scale adjacent said first line-length scale and a second justification-indicating scale adjacent said second line-length scale, the respective said justification-indicating scales having calibrations corresponding in spacing to the associated line-length scale, a corresponding calibration of each of said justification-indicating scales being in columnal alignment with each other.

2. A justifying rule, comprising in combination, an elongate flat strip, a first line-length scale arranged longitudinally along one face of said strip and graduated in letter-spacings for a certain kind of type, a second line-length scale arranged longitudinally along an opposite face of said strip and graduated in letter-spacings for a different kind of type, said line-length scales being coextensive on said strip and having coincident zero points, a zero-indicator slide on said strip bearing zero pointers adapted to cooperate with the respective said line-length scales, and a justifying slide on said strip having panels overlying the opposite faces of said strip, each panel bearing a justification-indicating scale adjacent the respective line-length scales, the respective said justification-indicating scales having calibrations corresponding in spacing to the associated line-length scale, a corresponding calibration of each of said justification-indicating scales being in columnal alignment with each other.

3. A justifying rule, comprising in combination, an elongate flat strip having abutments at each end, a first line-length scale arranged along a longitudinal edge on one face of said strip and graduated in letter-spacings for a certain kind of type, a second line-length scale arranged along an opposite longitudinal edge and an opposite face of said strip and graduated in letter-spacings for a different kind of type, said line-length scales being coextensive on said strip and having coincident zero points, a zero indicator slide on

said strip, having panels overlying the opposite faces of said strip, each panel bearing a zero pointer adapted to cooperate with the respective said line-length scales, said zero indicator slide 5 being engageable with one of said abutments to register the zero pointers at the zero of said line-length scales, and a justifying slide on said strip having transparent panels overlying the opposite faces of said strip, each panel bearing a justification-indicating scale adjacent the respective said line-length scales, the respective said justification-indicating scales having calibrations corresponding in spacing to the associated-line-length scale, a corresponding calibration of each 10 15 of said justification-indicating scales being in columnal alignment with each other, the calibrations of said justification-indicating scales projecting over the associated line-length scale.

4. A justifying rule, comprising in combination, an elongate body having a line-length scale graduated in letter spaces arranged along a longitudinal edge thereof, a slide on said body including a transparent panel presenting a zero 5 indicating line transverse to said scale, and a justifying slide on said body including a transparent panel having a series of letter-spaced transverse lines calibrated to form a justifying scale, each of said panels and the transverse lines 10 thereon projecting substantially beyond the line-length scale edge of said body so as to overlie a line of typing, with the rule body disposed along the typing line, whereby a justifying reading may be made through said panels. 15

WILLIAM G. TURQUAND.
